DOOR FASTENER

George M. Coffey, Ronan, Mont.

Application May 1, 1939, Serial No. 271,156

4 Claims. (Cl. 292—45)

This invention appertains to new and useful improvements in door fasteners especially adapted for automobiles and other vehicles, and the principal object of the invention is to provide a door latch which is easily controlled either in the opening or closing of the door and which will be self-tightening, thus eliminating door rattling.

Another important object of the invention is to provide a door fastener of the character stated which will be of simple construction, substantially fool-proof in operation and not susceptible to the ready development of defects.

In the drawings:

Figure 1 represents a sectional view taken substantially on a line 1—1 of Figure 2.

Figure 2 is a fragmentary horizontal sectional view.

Figure 3 is a fragmentary vertical sectional view through the latch in effected position.

Figure 4 is a sectional view taken substantially on a line 4—4 of Figure 3.

Figure 5 is a perspective view of the bolt wedge assembly.

Figure 6 is a top plan view of the latch assembly in closed position.

Figure 7 is a sectional view taken substantially on a line 7—7 of Figure 6.

Figure 8 is a side elevational view of the cam.

Figure 9 is a perspective view of the spring for the rollers.

Referring to the drawings, wherein like numerals designate like parts, it can be seen in Figures 1 and 2, that numeral 5 represents the body of the vehicle which at the jamb edge of the door opening is provided with the plate 6 suitably secured to the body 5 and this plate 6 has suitably secured thereto as at 7—7 a pair of arms 8—9, each carrying a roller 10. The upper edge of the arm 8 and the lower edge of the arm 9 is notched to receive the inwardly curved end portions 11 of the leaf spring 12, a lug 13 on the plate serving to prevent displacement of this spring 12. A lug 14 projects outwardly from the plate 6 to support the arm 8 and tends to keep the rollers 10 properly aligned with respect to the wedge bolt 15, this bolt 15 being carried by the jamb side of the case 16, this case being mounted on the edge of the door 17 opposed to the plate 6.

The case 16 has the outwardly extending lugs 18 through which the pin 19 is slidably disposed, this pin extending into the recess 20 of the wedge bolt 15 and being threadedly engaged as at 21 in the inner end wall of the said recess

20. Convoluted on the pin 19 and being interposed between the said inner wall of the recess 20 and the lug 19 is the compression spring 22.

The wedge bolt 15 is of wedge shape and has the laterally disposed web 23 which is slidably disposed through the slot 24 in the case 16. The inner end of the web 23 which has the guide flange 25 for wiping engagement against the inner side of the case 16 supports the roller 26 at its inner end.

A shaft 27 is journalled through one side wall 28 of the case 16 and has its other end reduced and journalled as at 29 in the opposite side wall 30 of the case 16. The outer end of the shaft 27 is provided with the operating handle 15 32. The shaft 27 at a point in the case 16 carries the cam wheel 33 for riding engagement with the roller 26. A catch and spring has one end anchored to the cam side of the case 16 as at 34 and its other end attached to the cam wheel 33.

As can be seen in Figure 6 and also in Figure 1, a pair of bosses, namely an upper boss 34 and a lower boss 35 are provided on the cam wall 36 of the case 16 and between these the 25 wedge bolt 15 normally protrudes. The bosses 34 and 35 have inboard bevels 37 to facilitate passing between the bosses 34 and 35 of the rollers 10 and outboard bevels 38 against which surfaces the rollers are held by the wedging 30 effect of the wedge bolt 15.

It can now be seen that when the door 17 is pushed to a closed position the rollers 10 will ride inwardly and push the wedge bolt 15 outwardly until the rollers 10 start riding on the 35 bevelled surfaces 38 whereupon the effect of the spring 22 will be to spread the rollers apart and thus prevent return of the rollers.

To release the wedge bolt 15, the handle 32 is rotated and this operates the cam 33 so that the roller 26 is moved outwardly, thus retracting the wedge bolt 15 so that the spring 12 can contract the rollers 10, thus freeing the door so that it can be readily swung to an open position without any further effort.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. A closure fastener comprising a swingably mounted roller, a bevelled keeper, and a yield-

ably mounted deflecting member for deflecting and holding the roller against the keeper, said deflecting member being provided with a laterally disposed rider, a cam rotatably mounted, 5 manual means for operating the cam, said rider being engaged with the rotary cam, said cam being operative by said manual means to actuate the rider and shift the deflecting member from roller engaged position.

10 2. A closure fastener comprising a swingably mounted roller, a bevelled keeper, and a yieldably mounted deflecting member for deflecting and holding the roller against the keeper, said deflecting member being provided with a laterally 15 disposed rider, a cam rotatably mounted, manual means for operating the cam, said rider being engaged with the rotary cam, said cam being operative by said manual means to actuate the rider and shift the deflecting member from 20 roller engaged position, said deflecting member being in the form of a wedge having a shank, a stationary member through which the shank is slidably, and a compression spring interposed between the stationary member and the wedge- 25 shaped member.

3. A closure fastener comprising a swingably mounted roller, a bevelled keeper, and a yieldably mounted deflecting member for deflecting and holding the roller against the keeper, said deflecting member being provided with a laterally 5 disposed rider, a cam rotatably mounted, manual means for operating the cam, said rider being engaged with the rotary cam, said cam being operative by said manual means to actuate the rider and shift the deflecting member from 10 roller engaged position and spring return means for the rotary cam.

4. A closure fastener comprising a pair of rollers, a pair of pivotal arms carrying the said rollers, a pair of beveled closure carried bosses 15 each having a beveled surface, a wedge member adapted to deflect the rollers to engage the beveled surfaces of the bosses, means for retracting the wedge member to release the arms and the rollers from the beveled bosses, and a spring member having its end portions disposed inwardly and adapted to engage the arms to force the same toward each other.

GEORGE M. COFFEY. 25
